TELEPHONE SYSTEM

Louis B. Appleton, New York, N. Y.

Application May 26, 1932, Serial No. 613,748

12 Claims. (Cl. 179—2)

My invention relates to novel apparatus for and methods of operating telephone systems and more particularly relates to novel apparatus for and methods of operating broadcasting telephone systems.

The use of telephone lines for broadcasting special features such as news, lectures, concerts and the like, is well known. In these systems, however, as in radio broadcasting, it is not possible to determine how many subscribers or "listeners-in" are receiving the broadcast, and the economical value thereof is accordingly not known.

There are many instances where a broadcaster has special information which he desires to sell to a specific group of "listeners-in" who would be willing to pay a fee for such service.

Accordingly, an object of my invention is to provide novel methods of and means for recording the number of "listeners-in" in a telephone broadcast.

A further object of my invention is to provide novel apparatus for and methods of making a special charge to subscribers calling a particular telephone number.

There are other objects of my invention which together with the foregoing will appear in the detailed description which follows in connection with the drawings in which:

Figure 1 diagrammatically illustrates an automatic telephone system embodying a preferred form of my invention.

Figure 2 is a circuit diagram representing a portion of a manual system embodying my invention; and

Figure 3 is a modified form of an automatic system for carrying out my invention.

In Figure 1 I have shown, for purposes of simplicity, only so much of the system as is necessary to make the invention clear, it being understood that standard equipment to complete the system may be added. A calling, a broadcast subscriber's line, and substation of the broadcast subscriber, is disclosed, with one connector for each calling subscriber to complete the connections between the calling subscribers and the called subscriber. It will be understood, however, that in each of these systems having more than one hundred lines, one or more selectors, and trunks arranged to be connected in series, may be interposed between the line switch and connector between the dotted rectangle having the legend "Selectors".

The invention will be best understood by describing the method of establishing connection between each of the calling subscribers and the called subscriber.

In the normal operation of my system, the called party, that is, the party who is to broadcast first, lifts his hook from his receiver, conditioning his system for connection by any number

of calling or listening-in subscribers. Ground is thereupon applied to the conductor 84 for the purpose to be explained in more detail hereinafter.

As will appear in the detailed description which follows, this enables any calling subscriber now to connect into his telephone. As each connection is made, a meter device is automatically operated thereby to provide an indication of the number of listeners-in. At the same time, the meter at the calling subscriber's substation is automatically operated a predetermined number of times to make a predetermined charge for this special call. The calling subscriber's telephone is also rendered non-operative to prevent the calling subscriber from carrying on any conversation at this time.

When the subscriber at substation 1 initiates the call which is to terminate in a connection to the broadcasting subscriber, he removes his receiver from a switch hook and the line relay 2 is energized over a circuit from ground through the battery 3, the line relay 2, back contact and armature 4, through the telephone dial 5, telephone transmitter 6, contacts at the switch hook 7, through the telephone 8, over the conductor 9, and armature 10 and its back contact, to ground.

The line relay 2 is energized and in turn completes an operating circuit for the motor magnet 12 from ground through battery 13, the motor magnet 12, its armature 14 and back contact, armature 15 and its front contact, back contact and armature 16, and over the test brush 17, selectors 21, test conductor 22, front contact and the armature 23 of the slow relay 24, conductor 25, armature 26 and its back contact, to ground.

This circuit, as is well known in the art, is only completed if the brushes 17, 18 and 19 are not in engagement with the terminals of an idle trunk, the line switch in the present case being of the rotary type for purposes of illustration. The completion of this circuit, however, energizes the motor magnet 12 which opens its own circuit at armature 14. Magnet 12 is intermittently energized and deenergized, moving the brushes 17 to 19 from one set of trunk terminals to another until an idle set is found.

The cut-off relay 31 during this time, although a circuit is completed for it from grounded battery 13 and the winding of the motor magnet 12, winding of the cut-off relay 31, and the front contact and armature 32 to ground, is not operated because its winding is short circuited by the circuit for the motor magnet 12 over the armature 15 and its front contact, as described above.

When, however, the motor magnet 12 has advanced the line switch brushes 17, 18 and 19 to the terminals of an idle trunk whose test terminal is characterized by the absence of ground potential thereat, the associated relay 24 is not ener-

gized, the motor magnet 12 is no longer operated and the short circuit around relay 31 is no longer effective. Relay 31 will thereupon be energized in series with the motor magnet 12 and over the circuit described above. The winding of the motor magnet 12, however, is such that this magnet is not effective when operated in series with the cut-off relay 31. On operation of the cut-off relay 31, the lines 33 and 34 of subscriber 10 are extended through the armatures 4 and 10 in engagement with their front contacts to the brushes 19 and 18, respectively.

This circuit extends through the selector 21 and the conductors 35 and 36 to windings of the relay 37 in series to ground and grounded battery, respectively. The relay 37 is energized over this circuit and at the front contact of its armature 38 completes an energizing circuit for the slow releasing relay 24.

20 The cut-off relay 31, at its armatures 10 and 4 which now disengage their back contacts, opens the energizing circuit for the line relay 2 described above. Relay 2, however, is sufficiently slow releasing so that the operating circuit of the cut-off relay 31 is maintained effective until the relay 24 is operated to complete a holding circuit for the cut-off relay 31 extending from grounded battery 13 through the motor magnet 12, armature 14 and its back contact, through the winding of the relay 31, front contact and armature 16, brush 17, selector 21, conductor 22, front contact and armature 23, and armature 26 and its back contact, conductor 41, armature 42 and its back contact, to ground.

35 For purposes of this description, it has been assumed that the calling subscriber's line has been extended through one or more selectors, depending on the size of the system, to the connector of Figure 1 through which the called subscriber's line may be reached. It has been previously described how the extension of the calling line to these subscribers results in the operation of relay 37.

The connector switch is now in condition to receive impulses corresponding to the tens digit of the broadcasting subscriber's number. The subscriber at 1 now operates his dial sender in the well known manner to transmit the tens series of impulses. In response to each of the impulses in this series, the impulse relay 37 retracts its armature but the slow releasing relay 24 does not release its armature during the normal interruption of its operating circuit at the front contact and armature 38 of relay 37. On each retraction of the armature 38 of relay 37, a circuit is closed from ground over armature 38 and its back contact, armature 43 and its front contact, winding of the change-over relay 44, primary motor magnet 45 and the side switch wiper 46 in its first position to grounded battery 47. On the first completion of this circuit the change-over relay 44 attracts its armature 51 and thereby completes a circuit from ground through armature 51 through the escape magnet 53 to grounded battery 47.

65 As is well known, the escape magnet 53 on its deenergization serves to advance the side switch wiper 46 one step. On each completion of the circuit described as extending through the change-over relay 44, the primary motor magnet 45 advances the brushes 57, 58, 59, and 60 of the connector one step in their primary movement. At the close of the ten series of impulses, the impulse relay 37 holds its armature attracted for an appreciable interval so that the change-over

relay 44 deenergizes, opening the holding circuit of the escape magnet 53 at the armature 52. The escape magnet 53 thereupon deenergizes to advance the side switch wiper 46 into its second position.

80 The connector switch circuits are now in readiness to receive the unit series of impulses transmitted from the calling subscriber's dial. In response to each of these impulses, the impulse relay 37 retracts its armature as in the case of the previous series of impulses, but the unit impulses are now effective to control the secondary motor magnet 61 over a circuit extending from ground over armature 38 and its back contact, armature 43 and its front contact, through the change-over relay 44, and through the secondary stepping magnet 61, and the second contact switch 46, through the battery to ground. The switch 46 it will be understood was moved to this second position on the operation of the change-over relay 44 described hereinbefore.

85 On the first completion of this circuit, the change-over relay 44 is again energized as in the case of the ten series of impulses and likewise holds the escape magnet 53, energized over the circuit traced hereinbefore. In response to each of the units impulses, the secondary motor magnet 61 has its operating circuit closed so that it operates the brushes 57 to 59 of the connector in a step-by-step movement in a secondary direction.

90 When the brush wipers 57, 58, and 59 come to rest on the contacts extending to the called subscriber's lines 81 and 82, an energizing circuit is completed for the relay 83 from ground to battery, contact 59, winding of the relay 83, conductor 84, contact 85, to ground. In the above it is assumed, as has already been explained before, that the called subscriber contrariwise to the present practice, has already removed his receiver from the hook at the time when the calls begin to come in and accordingly the contact 85 is closed, as indicated in the above described circuit.

95 The battery over contact 59, it will be noted, 100 also extends over the conductor 91, armature 92, and its back contact, to the contact 93 of a switch 94 through its brush 95 and the counting magnet 96, to ground. The switch 94 is provided with a plurality of contacts, each of which extends to a similar calling equipment so that each calling party prepares an energizing circuit over an individual contact of the switch 94 for the counting magnet 96. The wiper 95 is stepped from contact to contact by means of the stepping magnet 97. The stepping magnet 97 in turn is controlled over the contact 85 and, as is well known in the art, as its circuit is intermittently interrupted at the contact 98, it functions to step the wiper 95 from contact to contact. This operation, as will be obvious, takes place after the calling operator has removed his telephone from the hook and closed the contact 85.

105 When the wiper 95 engages the contact 93 individual to the calling equipment of a particular calling subscriber, a circuit is completed for the counting magnet 96, as described above. At armature 99, an energizing circuit is also completed for the relay 101 over the switch 100 which in turn opens the energizing circuit for the counting magnet 96 at armature 92 and locks itself over its armature 102 and its front contact and conductor 84 to the contact 85. This prevents energization of the counting magnet 96 110

more than once for that particular calling subscriber.

As has been explained heretofore, it is desirable that the calling subscriber in calling this particular number be charged with more than one telephone call because of the special nature of the service to be provided thereof. To this end, a further switch 103 is provided having a wiper 104 which is stepped from contact to contact by the stepping magnet 105 which also breaks itself on circuit intermittent at its own armature 106. The circuit for magnet 105 is completed from battery on conductor 91 when the switching operation is completed. As the wiper 104 is stepped from contact to contact, impulses are transmitted over the front contact and armature 108, conductor 107, armature 23 and its front contact, selector 21, conductor 17, armature 16 and its front contact, to the calling subscriber's meter magnet 109 of meter 110. In this manner, any desired number of operations of the calling transmitter meter may be obtained, making a special charge for calling this particular number.

25 When the brush 104' engages the last contact 107 on the switch 103 operated in the same shaft with switch 103, an energizing circuit is completed for the stepping magnet 105 which is independent of its own armature 106. Stepping magnet 105 is accordingly now maintained energized until the receiver is again placed on its hook and the contact at 85 is broken.

At the calling subscriber's station, the magnet 109 in addition to operating the meter 110, also drives brushes on switch 115 which engages contacts 116 when the predetermined number of charge impulses is received to provide a bypass around the telephone, preventing talking by the calling party.

40 When the called party hangs his receiver on the hook again, ground is removed from the conductor 84 and the relays 83 and 75 are deenergized, disconnecting the calling party from the system. At armature 108, the circuit to the calling party's meter is opened. Similarly, the circuit for the stepping magnets 97 and 105 are opened and these magnets are deenergized to step their wipers 95 and 104, respectively, back to their first normal contact. The locking circuit for relay 101 is also 45 deenergized, restoring the armatures 92 and 102 to their normal position and the apparatus is back to normal. Similar operations, of course, occur for each of the other calling subscribers, the apparatus in each instance being restored to 50 normal. As will now be clear, conversation in one direction only can be obtained in my improved system. The control of the connection is entirely with the called subscriber, who by lifting his telephone from the hook, conditions his circuits 55 to permit connection thereto and by restoring the telephone to its hook, disconnects all calling subscribers' connections. Provision is made for making a special charge to the calling subscribers and at the same time recording all of the calls made 60 to the called party's line.

In Figure 2, I have shown a manual telephone system to which my invention has been applied, and it will be more fully understood by reference to the following detailed description thereof.

75 The conductors 200 are ordinary telephone subscriber line terminating at one end at a subscriber's station 201 and at the other end in a central office 202. At the station 201, the usual telephone set 203 is provided for an ordinary telephonic purpose and a supplemental key 204 is

provided for associating with the line a broadcasting receiving equipment 205.

At the central station 202, the line terminates in the usual type of switching jack 206 whereby telephonic communication may be established through the cord circuit 207 between the line 200 and other lines terminating at the exchange. Normally the line 200 is connected over the armatures 208 and 209 and their back contacts of the relay 210 to the jack 206 but the circuit of the relay 210 is so arranged that the line may be disconnected from the jack 206 when the key 204 at the calling subscriber's substation is operated. This circuit then extends through the transformer 212 to the program distributing equipment 202 with which the broadcasting subscriber is provided for his special broadcast and which is common to a large number of lines, as indicated.

80 The central program equipment itself is illustrated at 202 and is of a very simple type consisting in its most fundamental form of an ordinary telephone transmitter and an energizing battery such as is in common use in telephone substations today.

85 At the central office, in addition to the usual line relay 215, a special relay 216 is bridged across the line, the latter relay operating when the key 204 is actuated by the subscriber to energize the relay 210 which functions to disconnect the line from the jack 206 and connect it to the program 90 equipment at 202 at the same time applying a busy tone to the sleeve conductor of the jack to notify the central operator when testing the terminal that the subscriber is using the line for receiving the program. The relay 210, as will 95 appear hereinafter, also functions to operate a metering device 217 consisting of a metering relay 218, a switch 219, and a stepping magnet 220 for the broadcast subscriber.

100 One contact on the switch 219 is individual to 105 the apparatus associated with the line 200 and each of the other contacts are individual to each of the other lines.

105 The line relay 215 is marginal and does not operate through the high resistance connection 110 established by the key 204 and will only operate when the line is closed through the low impedance telephone set 203 by taking the receiver from the switch hook. If the subscriber should desire to use the line for ordinary telephonic purposes, 115 the line relay 215 will operate as soon as the receiver is taken from the hook, thereby causing the line lamp 221 to glow. At the same time, it opens the circuit of the relay 210 to prevent the relay 216 from actuating the relay 210 to disconnect the line from the jack 206. The operator, upon observing the glowing of the line lamp, may 120 establish a connection in the usual manner by 125 means of a cord circuit 207.

130 If, upon an incoming call, the operator desires 135 to establish a connection with the line 200, the busy tone on the jack will be disregarded if the subscriber is receiving program service and a connection established by inserting the plug of the cord 207 in the jack 206. This operates the 140 cut-off relay 222 which in turn disconnects the special relay 216 and the line relay 210 from the line.

145 At the subscriber's station, the transformer 225, which serves to associate the loud speaking receiver 205 with the line, is provided with a condenser shunted by a high resistance winding of a polar relay 226. Owing to the high resistance of the latter, when the key 204 is thrown, only sufficient current flows through the bridge in- 150

cluding the windings of relays 216 and 215 at the central station to operate the relay 216, the line relay 215 not being operated when the set is used for program purposes. The polar relay 226 at the calling subscriber's station controls a relay 227 whereby the loud speaking receiver 205 may be disconnected from the line, even though the key 204 is actuated.

The polar relay 226 is so poled as to energize the relay 227 for this purpose only when battery is supplied to the line from the cord circuit 207, the battery connections through the windings of the relays 215 and 216 being reversed with respect to the cord circuit. Consequently, the relay 226 disconnects the loud speaking receiver only when the operator inserts the plug of the cord circuit 207 into the jack 206 to establish an ordinary telephone connection. This obviates any possibility of ringing current actuating the loud speaking receiver and annoying the subscriber. A low resistance relay 228 is included in series with the subscriber's set 203, said relay operating to disconnect the polar relay 226.

Loud speaking receiver 205 is controlled from the line 200 through an auxiliary relay 230 whenever the subscriber takes down the receiver to use his set for ordinary telephonic purposes. This arrangement is provided so that the special receiving equipment will be disconnected under these circumstances even though the subscriber should fail to restore the key 204.

The detailed operation is as follows: Assuming that the subscriber at station 201 desires to receive program services, the key 204 is actuated thereby closing a circuit through the winding of the high resistance polar relay 226, over the normal contacts 231 and 232 of the relay 230, over the make contacts 233 and 234 of the key 204, over the line 200, armatures 235 and 236 and their back contacts of the relay 222, and through the winding of the special relay 216 and the line relay 215.

The special relay 216 is operated over this circuit but the current flow is not in a direction to operate the relay 226. The marginal line relay 215 is not operated and hence the energization of the relay 216 completes a circuit from ground over the back contact of the line relay 215 and the front contact of the special relay 216 through the winding of the relay 210. The latter is energized to disconnect the line 200 from the jack 206 and connect the line to the program equipment over the armatures 208 and 209 and their contacts. At the same time, a busy tone is applied to the sleeve conductor of the jack 206 to appraise the central office operator when testing the terminal that the subscriber is receiving the distributed information.

The wiper of switch 219 is in operation, stepping from contact to contact by the intermittent operation of the stepping magnet 200 which has previously been started into operation by the depression of the key 244 started into operation just before the program is to be transmitted and when the calling subscribers begin to connect in on this circuit. As the brush of switch 219 engages the first contact, the circuit will be completed for the counting magnet 218 which will operate a counting device. At the same time, relay 220 is energized and locks itself over its front contact to prevent further energization of the relay 218 by this particular equipment.

When the apparatus is restored to normal, relay 220 will deenergize. Operation of the counting device at the calling subscriber's office to make a

special charge for this call, may also be provided in the manner described in Figure 1.

The actuation of the key 204 also serves to connect the loud speaking receiver 205 with the line over the normal contacts of the relay 227 through the transformer 225 and the normal contacts of the relay 230. The subscriber is now enabled to hear by means of the loud speaker 205, the information distributed from the broadcasting station 202.

If while the line is thus in use, a sufficiently urgent call should come into the central switching office for the line 200, the operator may disregard the busy tone on the sleeve of the jack 206, and insert the plug of the cord 207 into the jack 206, which thus completes a circuit over the sleeve of the jack 206 through the cut-off relay 222. The cut-off relay 222 is thereupon energized and operates to disconnect the special relay 216 and the line relay 215 from the line. Relay 215, upon

being deenergized, opens a circuit of the relay 210, which at once disconnects the line 200 from the station 202 and connects it to the tip and ring of the jack 206. The direct current supplied to the line 200 through the windings of the relays 215 and 216 was not in such a direction as to actuate the high resistance polar relay 226, but as soon as the cord circuit is connected to the line and the relays 216 and 215 disconnected, the direct current supplied through the cord will be in such a direction as to actuate the polar relay 226 and

close the circuit of the relay 227, which at once disconnects the loud speaking receiver 205 from the transformer 225. The relay 227 is locked over its right-hand front contact, right-hand back contact of relay 230 and lower make contact of key 204, so that said relay 227 will be held up independently of the polar relay.

The subscriber may now be rung in the usual manner by the operator and upon removing the receiver from the hook, the talking circuit will be established to the central office. Direct current from the central office battery flows through the cord circuit over the subscriber's line and through the relay 228, this relay being energized as long as the receiver is removed from the hook.

The relay 228 completes the circuit of the relay 230, which disconnects the program receiving apparatus from the line independently of the key 204 and at its right-hand contact opens a locking circuit of the relay 227 which is restored to normal.

At the end of the conversation, the subscriber may hang up his receiver, thereby giving the usual disconnect signal and deenergizing the relay 228 which (if the key 204 has not been restored) again connects the polar relay 226 to the line. Current flows through the polar relay in such a direction as to energize and lock up the relay 227. As soon as the operator withdraws the plug of the cord 207 from the jack 206, the cut-off relay 222 is deenergized, thereby again connecting the special relay 216 and line relay 215 to the line.

The line relay 215 is not energized but the special relay 216 is energized in series with the polar relay 226. The current flow is not in such a direction as to operate the polar relay 226 but the energization of the special relay 216 again completes a circuit of the relay 210 which disconnects the line 200 from the jack 206 and connects it to the broadcasting station 202. Transmission from the program station may again be received

by the loud speaking receiver 205 as soon as the subscriber restores the key 204 to unlock the relay 227 and then again actuates the key.

- If, while the line is being used for receiving distributed information, the subscriber should desire to use the line for establishing a telephone call, the receiver may be removed from the hook, thereby energizing, in addition to the already energized relay 216, the line relay 215 and the relay 228. The relay 228 actuates the relay 215 to disconnect the special receiving equipment independently of the key 204. The line relay 215 opens a circuit of the relay 210, which upon being deenergized, disconnects the line 200 from the program station and connects it to the jack 206. The line relay 215 at the same time completes a circuit of the line lamp 221 over its front contact. The operator will answer the call by inserting the plug of the cord circuit 207 in the jack 206 thereby causing the cut-off relay 222 to disconnect the relays 215 and 216 from the line as before so that the relay 210 remains deenergized with the line connected to the jack 206. At the end of the conversation the subscriber may hang up his receiver and the apparatus may be restored to the condition for program reception in the manner already described.
- When the subscriber no longer desires to receive the program service he will simply restore the key 204 thereby disconnecting the loud speaker and associated apparatus from the line and opening the circuit of the special relay 216. The latter, upon being deenergized, will open the circuit of the relay 210, which will disconnect the line from the program equipment at 203 and connect it to the jack 206.
- Figure 3 illustrates an arrangement for applying program service to telephone lines terminating at a central office equipped for machine switching. At machine switching offices no operators will be provided to exercise discretion with regard to the urgency of incoming calls and in practice the circuits might be arranged either to exclude all incoming calls while the special program equipment is in use or to permit all incoming calls to interrupt the program service. The circuit illustrated in Figure 3 is arranged so that when the line is in use for program receiving no incoming calls may be made. The subscriber himself, however, can interrupt the program service to make outgoing calls at any time by simply removing his receiver from the switch-hook as in the case of the circuit shown in Figure 2.
- In this form of the invention the equipment at the subscriber's station 301, both for program receiving and for ordinary telephonic purposes, is identical with that shown in Figure 2, except that the subscriber's telephone set is provided with the usual form of dial 302 for operating the switching machinery at the central office.
- The program equipment at the station 303 and its association with the line 304 at the central office is also identical with that illustrated in Figure 2. The line 304 terminates at the central office for the purpose of establishing incoming connections in the usual form of connector bank (not shown) while, for the purpose of establishing outgoing connections the line terminates in the well known Keith line switch and its associated master switch. As these elements are well known in the art, only a portion of the circuits thereof are illustrated and the detailed construction thereof need not be described. A marginal line relay 305 is provided, as in the manual system, this relay being only operated when the receiver is removed from the switch-hook. The line relay controls a double wound plunger magnet 306 of well known construction, which performs the double function of acting as a cut-off relay and of operating the plunger 307 to connect the line to the dial-operated switching machinery (not shown). The windings of the plunger magnet, as is well known, are so arranged that the upper winding, when energized, will cause the plunger 307 to operate. The lower winding, however, will not operate the plunger 307 but will only hold the plunger 307 in operated position if it has already been operated. In addition to the marginal line relay 305, a special relay 308 is provided, as in the manual system, said relay 308 functioning, if the line relay 305 is not energized to complete the circuit of the relay 309, which disconnects the line from the jack 310 and connects it to the program equipment at 303.
- Further details of the invention will be understood from the description of the operation which is as follows: Assuming that the subscriber desires to receive distributed information or the like. The key 311 is actuated to connect the high impedance polar relay 312 and the loud speaking receiver 313 to the line as before.
- This established a direct current circuit from battery through the line relay 305, through the winding of the special relay 308, over the upper contact of the plunger magnet 306, through a winding of the retard coil, to the tip side of the line 304, upper make contact of the key 311, left-hand contact of the relay 314, make contact of the key 311, ring side of the line 304, through the right-hand winding of the retard coil at the central station and over the lower contact of the plunger magnet to ground, through the circuits of the master switch (not shown). The current flowing through this circuit is not sufficient to operate the line relay 305 and is not in such a direction as to operate the polar relay 312. The special relay 308 is operated, however, and completes a circuit for the relay 309, which disconnects the line 304 from the connector bank terminals and connects it to the station at 303, so that distributed information from said station 303 is transmitted over the make contacts of the relay 309 and over the line 304 to the loud speaking receiver 313. It will be noted that while the line is in this condition a busy potential is applied to the sleeve conductor leading to the connector bank at the central office, over the lower front contact of the relay 309. Therefore, if, while the line is being thus used, some other subscriber desired to converse with the subscriber on the line 304, the switching machinery (not shown) operated at the central station in a well known manner to establish connection with the line 304, will find the busy potential upon the sleeve and will therefore fail to establish a connection with the line. The program service cannot be interrupted by an incoming call, therefore, if the special receiving equipment is in use.
- A further result of the energization of relay 309 is to operate armature 315 to its front contact, completing an energizing circuit for relay 316 which in turn at its armature 317 completes an energizing circuit for relay 318 and counting magnet 319 of the switch 320. Switch 320 is operated by stepping magnet 321 in the manner described in Figure 2 to step the magnet 319 of switch 320 from contact to contact while broadcast listeners are making connections thereto. This makes a record of the number of subscribers listening in. Energization of relay 318 opens the circuit to the counting magnet which accordingly is operated only once for this particular calling party. If

desired, the calling subscribers may be made a special charge for this service in the manner described in connection with Figure 1.

If, while the program receiving apparatus is associated with the line by means of the key 311 so that the loud speaker 313 is being operated, the subscriber at station 301 should desire to use the line for ordinary telephone purposes the subscriber may remove the receiver from the switch-hook, thereby establishing a low resistance connection over a circuit through the line relay 305, special relay 308 and the relay 314'. Relay 314' is energized and completes the circuit of relay 314, thereby disconnecting the loud speaking receiver and associated equipment from the line independently of the key 311. The marginal line relay 305 is operated over the low resistance circuit through the substation set and its left-hand contact opens a circuit of the relay 309, which upon being deenergized disconnects the line from the central program station. Over its right-hand contact the line relay 305 completes a circuit through the upper winding of the plunger magnet 306 (the portion of this circuit extending through the master switch is not shown).

The plunger 307 is actuated by means of the upper winding of the plunger magnet to complete a circuit from the line 304 over the switches controlled by the plunger magnet to the selector switches (not shown). The plunger magnet, upon being energized, disconnects the line relay 305 and special relay 308 from the line. Both relays are now deenergized so that the circuit of the relay 309 is maintained open. The actuation of the plunger switch completes a circuit from battery, through the lower winding of the plunger magnet and over the inner right-hand contact of the plunger switch (the complete circuit not being shown). The lower winding of the plunger magnet remains energized during the entire connection to hold the plunger in actuated position. The upper operating winding of the plunger magnet is deenergized as soon as the armature of the line relay falls off.

The line circuit 304, having been extended over the contacts of the Keith line switch under the control of the plunger 307 to the tip and ring conductors extending to the selector (not shown), the subscriber may manipulate the dial 302 in a well known manner, thereby transmitting impulses over the line to the switching machinery and establishing the desired connection. At the conclusion of the conversation, the subscriber at the station 301 hangs up his receiver. This causes a release of the switching machinery in a well known manner. As soon as the switching machinery is released the ground applied through such machinery to the conductor marked "Release" at the station 322 is removed therefrom, thereby opening the holding circuit extending over the inner right-hand contact of the plunger switch to the holding winding of the plunger magnet 306. The plunger magnet is now deenergized, releasing the plunger 307 which disconnects the line from the switching apparatus. The plunger magnet, upon deenergizing, also connects the line relay 305 and special relay 308 to the line over the circuit previously traced.

Relay 314' is deenergized when the receiver is hung up so that the loud speaking receiver and associated equipment is again connected to the line. The line relay 305 remains deenergized because of the high impedance of the polar relay 312. The special relay 308 is energized, however, and again completes a circuit of the relay

309 so that the line may be again connected to the program receiving equipment and placed in condition for receiving the distributed information as before.

If the subscriber desires to terminate the reception of distributed information he merely restores the key 311 to normal, thereby opening the circuit through the line relay 305, special relay 308 and polar relay 312. The loud speaking receiver and associated equipment is now disconnected from the line at the contacts of the key 311. The deenergization of the special relay 308 results in opening the circuit of the relay 309, which thereupon disconnects the line 304 from the program equipment at station 303 and connects the line to the switching terminals.

If, while the line is not being used either for ordinary telephone purposes or for program receiving a connection should be initiated through the switching machinery (not shown) for the line 304, no busy ground would appear at the sleeve conductor of the connector bank and consequently the connector would make the connection with the line terminals and complete a circuit over the sleeve conductor and the lower back contact of the relay 309 through the holding winding of the plunger magnet 306. The plunger magnet would be energized sufficiently to disconnect the line relay 305 and special relay 308 from the line 304, thereby preventing any possibility of the relay 309 being operated to disconnect the line from the connector bank.

The battery current supplied over the line through the connector will flow in the opposite direction from that supplied from the line relay 305 and special relay 308 and therefore, if the subscriber should inadvertently or otherwise operate the key 311 after such a connection has been established and before the receiver is removed from the switch-hook, the polar relay 312 would be energized in such a direction as to operate the relay 333, thereby disconnecting the loud speaking receiver 313 from the line. If the subscriber, upon receiving a ringing signal from the connector switch, removes his receiver from the switch-hook, the relay 314' will be operated, thereby in turn completing the circuit of the relay 314 and disconnecting both the polar relay 312 and the loud speaker 313 from the line.

Although I have illustrated my invention by a specific circuit arrangement, it will be obvious that other automatic manual exchanges may embody my invention as I do not intend to be limited by the specific illustration except insofar as set forth in the appended claims.

I claim:

1. In a telephone system, a called subscriber's station; a plurality of calling subscribers' stations; means for normally permitting two-way communication between any of said subscriber stations; means including circuit connections for simultaneously connecting any number of said calling subscribers to said called subscriber simultaneously for the broadcast of a program; storing means, and means including said storing means at said called subscriber's station automatically responsive to an incoming call for indicating the totalized number of all such calling subscribers during said program.

2. In a telephone system, a called subscriber's station; a plurality of calling subscribers' stations; means for normally permitting two-way communication between any of said subscriber stations, automatic means including circuit connections for simultaneously connecting any

station; a plurality of calling subscribers' stations each having a meter; means for normally permitting two-way communication between any of said subscriber stations; manual means including circuit connections for simultaneously connecting any number of said calling subscribers to said called subscriber simultaneously for the broadcast of a program; storing means; means including said storing means at said called

subscriber's station automatically responsive to an incoming call for indicating the totalized number of all such calling subscribers during said program; and means for automatically operating the calling subscribers' meters a plurality of times to make a special charge for said connection. 80

LOUIS B. APPLETON.
